W. A. LORENZ

CLOSURE FOR CONTAINERS

Filed May 2, 1923

Inventor:
William A. Lorenz

UNITED STATES PATENT OFFICE.

WILLIAM A. LORENZ, OF HARTFORD, CONNECTICUT.

CLOSURE FOR CONTAINERS.

Application filed May 2, 1923. Serial No. 636,265.

To all whom it may concern:

Be it known that I, WILLIAM A. LORENZ, a citizen of the United States, residing at Hartford, in the county of Hartford and 5 State of Connecticut, have invented new and useful Improvements in Closures for Containers, of which the following is a specification.

This invention relates to improved means 10 for closing the tops of jars, tumblers or other containers. This closure is adapted for sealing receptacles containing cold products without the use of a vacuum; or for sealing receptacles by the well known vacuum process. 15

The sealing of containers for holding food products especially, present difficulties which are quite serious. These comprise the proper seating of the cap and gasket on the jar rim, 20 and holding them in place while the sealing operation is carried on; and other difficulties are also to be overcome.

The object of the present invention is to provide a closure that will hold the gasket in 25 the cap so that the cap with the gasket can be placed on the jar or container and thus obviate the placing of a gasket on the container itself by hand.

Another object consists in exerting pressure 30 on the inside of the annular gasket during the sealing operation, so that as the sealing operation is carried on, the gasket will be pressed outwardly and over the rim of the receptacle, and thus force the gasket itself down over the outer rim of the receptacle.

In the drawings Figures 1 and 2 show an outside view and a sectional view, respectively, of a cap having spring finger devices 40 for holding the gasket in position in the cap. Fig. 3 shows the cap of Fig. 2 in section, placed upon a container ready to be sealed. Fig. 4 shows the cap of Fig. 3 pressed down upon the container and held by atmospheric 45 pressure, thus completing the sealing operation. Fig. 5 shows an enlarged view of a part of Fig. 3, and Fig. 6 is an enlarged view of a part of Fig. 4. In both of these figures the left hand edge only is shown. Fig. 7 shows a modification of the cap of Fig. 3. Fig. 8 shows another modification of the cap; and Fig. 9 shows a further modification of the cap.

The container 10 may be of any desired 55 form. It is provided with a rounded rim 11. In the drawings a tumbler is shown whose

rim 11 may be fire finished, if preferred. The closure, or cap 14, may be formed from a circular blank with a turned down rim 15; or it may be formed from a rectangular blank, thus forming recesses 16-16 as in Fig. 7. The annular elastic gasket is shown at 18 in Figs. 2, 3, 5, 7, 8 and 9 in its non-compressed condition.

In order to hold the gasket 18 in place, 65 the rim 15 of the cap is perforated at intervals, forming spring projections 19-19. These are bent inwardly so as to reach below the gasket 18.

The cap 14 is also provided, next to the 70 rim 15, with an angularly bent annular portion 20, extending from the rim 15 downwardly. This angularly bent portion 20 may terminate in an annularly projecting portion 21, and beyond that the central portion of 75 the cap is shown at 22, which may be raised from the lower portion of the part 21; or it may extend inwardly as shown at 23 in Fig. 8.

It will be noted that the angularly bent 80 portion 20 on its under side faces downwardly and outwardly, and that the cap is not provided with any opposition to portion 20, or with any means for camming or forcing the gasket inwardly and downwardly. More 85 specifically, it will be seen in the figures that the rim is generally cylindrical and is not curved at its upper end over the mouth of the jar, and further that the portion 20 meets the top of the rim at a sharp angle. Thus 90 the portion 20 is free to force the gasket to the position shown in Fig. 6 and there is no force which tends to squeeze the gasket radially inwardly.

In Fig. 7 the spring projections are shown 95 at 24-24.

When placing the cap on the container, the spring fingers 19 will be sprung outwardly a little, in case they have been bent inwardly more than the difference between the cap 100 rim 15 and the container 10. This is shown in the enlarged view Fig. 5.

When sealing the container 10 of Figs. 3 and 5, the cap 14 with its gasket 18, is placed loosely upon the container; air is pumped 105 out from the interior of the container by suitable means; then the cap is forced downwardly, compressing the gasket 18 approximately to the form 26 of Figs. 4 and 6. During this compressing operation the angular 110 part 20 of the cap 14 will force the gasket 18 outwardly, over and beyond the rim 11,

and will force the gasket downwardly over its rim as at 27, thus making a very effective sealing of the container.

A modification of the gasket holding device 19, is shown in Fig. 9, in which the rim 15 of the cap 14 is pressed inwardly at intervals as at 30, forming projections which enter the gasket 18 and thus hold it in position in the cap. These projections 30 may be used independently of the spring fingers 19, or in conjunction therewith, if preferred. Various modifications may be made without departing from the spirit of the invention.

I hereby claim as my invention:

- 15 1. In combination a cap for a container having a rim portion provided with inwardly bent projections and a gasket situated in said cap and held engaged and in position therein by said projections.
- 20 2. A closure for containers comprising a

cap having a rim provided with spring finger projections extending inwardly from the rim of the cap, and a gasket within said cap and overhanging and engaging the tops of said fingers, whereby the gasket is held 25 in said cap.

3. A closure for containers having a rim portion with projections engaging and holding the gasket in position in the cap, and having an angularly disposed portion of the 30 top of the cap adjacent to the rim portion, bent downwardly and inwardly, for forcing the gasket outwardly during the sealing operation.

Signed at Hartford, Conn. this 27th day 35 of April 1923.

WILLIAM A. LORENZ.
